(57) **CLAIM**

The ornamental design for a vehicle tire, as shown and described.

DESCRIPTION

FIG. 1 is a front perspective view of a vehicle tire showing our new design;

FIG. 2 is a front elevation view of thereof;

FIG. 3 is a rear elevation view of thereof;

FIG. 4 is a side view of thereof;

FIG. 5 is an opposing side elevation view of thereof;

FIG. 6 is a top plan view of thereof;

FIG. 7 is a bottom plan view thereof; and,

FIG. 8 is an enlarged front view thereof, wherein the enlargement area is indicated by the bracket marked FIG. 8 in FIG. 2.

The even broken lines in the drawings illustrate portions of the vehicle tire that forms no part of the claimed design. Additionally, the dash-dot broken lines indicates the boundaries of the claimed design and also forms no part of the claimed design.
